UNITED STATES PATENT OFFICE.

DAVID MCF. MOORE, OF FRANKLIN, PENNSYLVANIA.

DESIGN FOR A CASE FOR ACCOUTREMENTS.

SPECIFICATION forming part of Design No. 32,614, dated May 1, 1900.

Application filed March 20, 1900. Serial No. 9,462. Term of patent 14 years.

To all whom it may concern:

Be it known that I, DAVID MCF. MOORE, a citizen of the United States, and a resident of Franklin, county of Venango, State of Pennsylvania, have invented and produced a certain new and original Design for Cases for Accoutrements; and I do hereby declare that the following is such a full, clear, and exact description of the same as will enable others skilled in the art to which the invention relates to make and use the same, reference being had to the accompanying drawing, forming part of this specification, which is a perspective view of the case looking from a point above and to one side of the same.

The device is a traveling-case or hand-trunk for military accoutrements or the regalia of Knights Templar and other organizations. It consists of a body portion *a*, which is rectangular in form and is provided at one end only with an extension *b*, the opposite end *c* being shallow and of substantially the depth of the top *d*, which is also shallow and rectangular in form, so as to conform closely in contour

to the outlines of the body portion at the top. 25 The extension *b* has a straight bottom *e* running for a short distance parallel with the upper edge of the body. From the point *f* the bottom of the case is curved upwardly and toward the opposite end of the case, as shown 30 at *g*, the curvature forming a graceful arch from the bottom of the extension outwardly to the opposite end of the body *a*. The top *d* of the case is provided with an ornamental handle *h* and clasps *i i*. A lock-plate or escutcheon *j* is also provided about midway between the clasps, giving to this side of the case a tasteful and ornamental appearance. 35

Having thus described my invention, what I claim, and desire to secure, is—

The design for a case for accoutrements herein illustrated and described. 40

In testimony whereof I affix my signature in presence of two witnesses.

DAVID MCF. MOORE.
